UNITED STATES PATENT OFFICE

ARTHUR H. FETTERS, OF OMAHA, NEBRASKA, ASSIGNOR TO GENERAL STEEL CASTINGS CORPORATION, OF GRANITE CITY, ILLINOIS, A CORPORATION OF DELAWARE

LOCOMOTIVE CONSTRUCTION

Application filed October 1, 1928. Serial No. 309,618.

My invention relates to railway rolling stock and consists in a new locomotive framing structure.

The main object of my invention is to combine the locomotive bed or main frame and associated parts with a reservoir for compressed air in such manner as to form a stronger frame and to eliminate the necessity for the usual separately formed reservoirs at the sides of the boiler or superstructure.

By means of my invention, I can embody the air reservoir in the main frame at little or no additional cost of the latter and I eliminate the expense of the steel reservoirs heretofore used and eliminate the maintenance of the latter, and provide additional space at the side of the boiler shell for other purposes.

20 In the preferred embodiment of my invention, the air reservoir and main frame or bed are formed integrally in a one piece casting which also includes the pedestals, equalizer fulcrums, brake hanger and spring hanger bearings, expansion plate brackets, cradle, deck plates, boiler saddle, pilot beam and steam cylinders.

It will be understood that the inclusion of all these elements is unnecessary to the 30 use of the essential features of my invention.

In the accompanying drawings which illustrate my invention—

Figure 1 is a one half longitudinal top view of the locomotive bed.

35 Figure 2 is a side elevation of the same with superstructure.

Figure 3 is a vertical transverse section taken approximately on the line 3—3 of Figure 1.

40 Figure 4 is a similar section illustrating a modified form of my invention.

In all of these figures the wheels are indicated in dot and dash lines.

The frame includes spaced side members 1, preferably of box cross section, having pedestal jaws 2, equalizer fulcrums 3, and brake hanger brackets 4 formed integrally therewith. The rear ends of side members 1 are extended to form the cradle sides 5 which are connected at their rear ends by

a deck plate 6 having extensions 7 for mounting the side bearings (not shown) which will rest upon the trailer truck frame (not shown). The forward ends of side members 1 merge with each other and are extended forwardly to form a front deck 8 terminating in the pilot beam 9. The boiler saddle is indicated at 10 and is preferably formed integral with the side members and deck and cylinders 11.

Between side members 1, I provide a main longitudinal member 12 which forms the "backbone" of the bed and transmits buffing and pulling forces and also reinforces the frame transversely and vertically. By making member 12 hollow and closing its ends, I adapt the same to be used as an air reservoir taking the place of the usual tanks made of sheet steel and mounted at the side of the boiler shell. The boiler is shown at 13 A and the air compressor at B, the pipe connections between air pump and reservoir being indicated at C.

In my preferred construction, I illustrate member 12 as being of cylindrical shape and in order to support the cores in the mold and to provide for the escape of gases during the casting operation, I provide suitable openings in the top and bottom walls of the reservoir. After the casting is completed, and the core sand removed, these openings can be closed by means of the plates 13. The openings are elongated so that each plate can be inserted lengthwise and then turned to the position shown. The plates 13 may be welded in position, as indicated at D, or they may be sealed in place by bolting or other clamping means.

Members 1 and 12 are connected by vertically spaced webs 14 which unite with the adjacent walls of members 1 and 12 to form a substantially continuous box shaped member on each side of member 12, thus further reinforcing the frame and providing a structure which is rigid and adapted to resist deflection in every direction. Webs 14 may be perforated at intervals, as indicated at 15, to provide for application of driver spring saddles 27 on top of driving boxes 16.

and to lighten the casting and improve casting conditions.

It may be desired to reinforce member 12 transversely of the frame, and I show a brace 16 for this purpose extending across member 12 preferably for the full length of member 12 and located at the level of top webs 14. Openings 28 are provided in brace 16 for molding purposes and for lightening the casting.

Brackets 18 for the expansion plates P will be formed integrally with side members 1 and member 12. Where there is sufficient space between member 12 and the boiler 17, brackets 18 may extend clear across the frame further reinforcing it transversely. Where this space will not permit a continuous bracket, or same is not desired for other reasons, the bracket may be divided as shown (Figure 3).

In Figure 4 I illustrate a modified construction in which the side members 21 and the parts associated therewith are substantially the same as in the preferred construction, but the central backbone air reservoir forming member 22 is illustrated as being of rectangular or box shaped cross section and the longitudinal brace 23 which preferably will extend the full length of member 22 is disposed vertically rather than horizontally, as does brace 16 in the preferred construction. A series of openings 30 are provided in brace 23 for molding purposes and for lightening the casting. The openings in member 22 are closed by means of plates 29 welded to the casting at W.

The connection between the central member and the side members comprises spaced horizontal webs 26, which, with the adjacent walls of members 21 and 22, form a box shaped connection between the center and side of the underframe.

I contemplate the exclusive use of these and other modifications in the details of construction of my device which come within the scope of my claims.

I claim:

1. A locomotive underframe including driver pedestals and having an air reservoir forming a part of the underframe.
2. In a locomotive underframe including driver pedestals, and a backbone member forming an air reservoir.
3. In a railway locomotive underframe, spaced hollow side members each including a series of pedestals, and a longitudinally disposed hollow member between said side members and connected therewith and forming an air reservoir.
4. In a railway locomotive underframe, spaced hollow side members each including a series of pedestals, a longitudinally disposed hollow central member between said side members and forming an air reservoir, and a hollow member on each side of said

central member connecting the same with the adjacent side member.

5. A railway locomotive frame comprising spaced hollow side members, each forming a series of pedestals, a longitudinally disposed hollow central member located between and spaced from said side members and extending substantially the length of the pedestals and forming an air reservoir, and a substantially continuous connection between said central member and each of said side members.

6. A railway locomotive frame comprising spaced hollow side members, each forming a series of pedestals, a longitudinally disposed hollow central member located between and spaced from said side members and extending substantially the length of the pedestals, and transverse braces between said side members and extending through said central member.

7. A railway locomotive frame comprising spaced hollow side members, each forming a series of pedestals, a longitudinally disposed hollow central member located between and spaced from said side members and extending substantially the length of the pedestals, and transverse braces connecting said central member and side members and formed integrally therewith.

8. In a locomotive bed, side members including wheel pedestals, a cradle at one end of said members terminating in a rear deck, a front deck and pilot beam at the other end of said members, and an air reservoir located between said members and extending from said cradle to said front deck and adapted to transmit buffing and pulling forces.

9. In a locomotive frame, side members including pedestals, a hollow central member between said side members forming an air reservoir and extending above said side members, and braces connecting said side members and said central member.

10. In a locomotive underframe, hollow side members having pedestals extending downwardly therefrom, a centrally located hollow member forming an air reservoir and projecting above and below said side members, and transverse braces connecting said central member and said side members.

11. In a locomotive bed, side members including wheel pedestals, a cradle at one end of said members terminating in a rear deck, a front deck and pilot beam at the other end of said members, and an air reservoir located between said members and extending from said cradle to said front deck and adapted to transmit buffing and pulling forces, all of said structure being formed in a one piece casting.

12. In a railway locomotive underframe, spaced hollow side members each including a series of pedestals, a longitudinally dis-

posed hollow central member between said side members and forming an air reservoir, and a hollow member on each side of said central member connecting the same with the adjacent side member, all of said members being formed in a one piece casting.

13. A one piece locomotive frame casting comprising an elongated hollow member forming an air reservoir, side members connected to said hollow member and forming wheel pedestals, and brackets for mounting the locomotive boiler.

14. A one piece locomotive frame casting comprising an elongated hollow member forming an air reservoir, side members connected to said hollow member and forming wheel pedestals, and brackets for mounting the locomotive boiler, equalizer fulcrums, and brake hangers.

15. A locomotive underframe casting including driver pedestals and having an air reservoir as an integral part of the casting.

16. A locomotive underframe casting including an air reservoir extending longitudinally thereof and forming the main longitudinal force transmitting member of the underframe.

17. In a locomotive underframe casting, driver pedestals, and a hollow longitudinally extending member adapted to contain air under pressure located in the space abreast of said pedestals.

18. A one piece locomotive underframe casting comprising a hollow longitudinally extending member comprising an air reservoir, and a brace inside of and extending substantially the full length of said member.

19. In a one piece locomotive underframe casting comprising side members, a hollow longitudinally extending member comprising an air reservoir located between said side members, and a brace inside of said reservoir alined with the top of said side members.

20. In combination, a hollow casting comprising a locomotive frame member including driver pedestals and adapted to transmit longitudinal forces and provided with openings in its wall to admit core supports and to permit discharge of core sand, and plates inserted in said openings and secured to the edges thereof to seal the same to close off the interior thereof to adapt said member for use as an air reservoir.

21. In a locomotive, an underframe including driver pedestals and having a reservoir member forming a main longitudinal force transmitting element of said underframe, and an air pump mounted on said locomotive and connected to said reservoir.

22. A locomotive underframe casting including driver pedestals and having a closed reservoir for compressed air extending longitudinally of the underframe and forming

the main longitudinal force transmitting member of the underframe.

23. A locomotive underframe including driver pedestals and having a closed reservoir for compressed air as a part of the underframe.

24. In a railway locomotive underframe, spaced side members including driver pedestals and a reservoir member connecting and bracing said side members.

25. In a railway locomotive underframe, spaced side members including driver pedestals and a reservoir member located between said side members and extending alongside of and substantially throughout the pedestal-forming portion of said members, and a substantially continuous connection between said side members and said reservoir member.

26. In a railway locomotive frame, side members including pedestals, a hollow central member between said side members forming a closed air reservoir for air under high pressure, and braces connecting said side members and said central member.

27. In combination, a locomotive underframe including spaced side members with pedestals, and a hollow closed reservoir adapted to contain air under high pressure arranged between said side members and connected therewith to reinforce the underframe.

28. A locomotive underframe including an air reservoir as an integral part thereof.

29. In a locomotive underframe, a reservoir for air under pressure forming a structural part of the underframe.

30. A locomotive underframe integral structure including a reservoir for air under pressure and provided with internal cross braces.

31. In a locomotive underframe, a main hollow backbone member extending longitudinally of the frame, there being transverse webs in said member whereby at least a portion thereof forms a closed reservoir for storing air under pressure.

32. A cast structure comprising a locomotive underframe and including as an integral part thereof a reservoir for storing air under high pressure to operate the train air brakes and similar equipment.

33. A railway locomotive frame comprising spaced side members, each forming a series of pedestals, a longitudinally disposed hollow central member located between and spaced from said side members and forming a reservoir for compressed air, and a substantially continuous connection between said central member and each of said side members.

In testimony whereof I hereunto affix my signature this 19th day of September, 1928.

ARTHUR H. FETTERS.
